UNITED STATES PATENT OFFICE.

JOSEPH C. LUKACHOVIC, OF DUNELLEN BOROUGH, NEW JERSEY, ASSIGNOR, BY MESNE ASSIGNMENTS, TO RANSOME CONCRETE MACHINERY COMPANY, OF PLAINFIELD, NEW JERSEY, A CORPORATION OF NEW JERSEY.

POWER LOADING APPARATUS.

Application filed November 23, 1923. Serial No. 676,658.

To all whom it may concern:

Be it known that I, JOSEPH C. LUKACHOVIC, a citizen of the Republic of Hungary, and a resident of the borough of Dunellen, 5 Middlesex County, State of New Jersey, have invented certain new and useful Improvements in Power Loading Apparatus, of which the following is a specification.

The improvements relate primarily to 10 apparatus for loading or charging concrete mixers and the like, in which a charging bucket or hopper is so mounted as to receive a charge of materials to be mixed at or near the ground, and is provided with 15 hoisting means whereby it is raised and caused to dump its load into the mixing drum. They are adapted however to be used for other and analogous purposes, with necessary modifications. The invention 20 nevertheless in so far as it is designed for use in connection with the particular apparatus referred to has certain features which distinguish it from other hoisting apparatus whether used to operate mechanism for loading or unloading materials or 25 for other purposes, and therefore while certain features of the invention are of broad application, other features are intended to co-operate with and are to be considered 30 solely in combination with the apparatus described and shown, the entire apparatus set forth in the claims constituting a new and useful combination.

Among the objects of the improvements 35 are the production of a differential hoisting mechanism which will act with increased and decreased power and decreased and increased speed at different stages of its operation to accommodate an increase or decrease of the load, automatically, and without the necessity for regulating the source of power or adjusting any of the parts, and without utilizing mechanism involving movements which cause an undesirable 45 change in the relative positions of the parts; the avoidance of unnecessary friction and strain in such an apparatus; and the construction and arrangement of the parts in such a manner that they may be varied if 50 desired to meet different specific uses, without changing the general construction and arrangement or necessitating redesigning. Other objects and advantages will be apparent to those skilled in the art.

The improvements are illustrated in the 55 accompanying drawings, in which Fig. 1 is an end elevation of a hoisting and lowering apparatus involving the improvements, and Fig. 2 is a side elevation thereof, certain parts of the mechanism in connection with 60 which it is used being shown diagrammatically.

In the drawings 1 represents a shaft 65 mounted in suitable bearings 2, 2' on a portion of the frame of the machine, shown at 3. 4 is another shaft mounted on a part 5 of the frame. Drums 6 and 6' are keyed to the outer portions of the shaft 1, and on the outer portions of the shaft 4 sheaves 7 are mounted for rotation. On the drums the 70 cables 8, 8' are adapted to be wound, these cables passing over the sheaves 7 and extending down to the loading bucket or hopper 9. The drums have grooves therein to receive the cables, and are fixed against 75 longitudinal as well as rotary movement on their shaft, while the sheaves 7 are permitted to move lengthwise of their shaft to a limited extent as the drums wind, so that the cables will at all times be substantially vertical and in line with the grooves 80 of their drums and sheaves, and so that undue friction and strain on the said parts and danger of the cable jumping its groove are avoided. The sheaves are limited in their 85 outward movement by the heads 10.

On one end of the shaft 3 the conical drum 11 is keyed, so that the shaft can be rotated thereby at varying speeds, and rotating power applied thereto in varying degrees. To this end the drum is provided with a spiral groove 12 on its face, the diameter of which increases and decreases with the diameter of the drum, and in this groove a cable 13 is wound. The opposite 90 end of the cable 13 is adapted to be wound on the grooved tapering drum 14 keyed to a shaft 15 which is connected with a suitable source of power, and is disposed at right angles to the shaft 1. The length of 95 the drum 14 is approximately equal to the distance radially from the outer end of the groove 12 to its inner end on the drum 11, and as the arrangement of the shafts of the two drums places the drum 14 substantially 100 parallel with the winding surface of the drum 11, and the cable winds on one drum 105 as it unwinds from the other, the said cable

will be at all times substantially vertical and approximately in line with the grooves of the drums. Therefore in the winding and unwinding operations the cable will enter the grooves of the two drums without any unnecessary friction or strain, thus avoiding wear and unnecessary strain on the cable and the drums, prolonging the life of both, and saving a certain amount of power.

10 As the cable 13 is wound on the drum 11, when the hopper 9 is lowered, and unwound from the drum 14, at the start of the hoisting operation the drum 11 will rotate slowly, and at the same time, owing to the great superiority of its diameter over the diameter of the drum 14 the power will be at its maximum. As the drum 14 winds the cable the speed of the winding, and consequent momentum of the hopper, increases and the 15 power decreases. It will thus be seen that the maximum of power and minimum of speed are at the beginning of the hoisting operation, where the load is greatest, and that when the hopper is lowered the application of a brake upon shaft 15 will have a greater tendency to check the descent of the hopper as the hopper nears the ground, thus providing for an acceleration of speed and decrease of power as the hopper is raised 20 and an increase in braking power and decrease in speed as it is lowered. At the same time the construction and arrangement of the drums and sheaves is such that the hoisting and lowering movements may take place 25 with great speed, regardless of the load carried, without undue friction, and without danger of either of the cables slipping from its grooves.

It will also be seen that the drums may be 40 removed and replaced by other drums, and the hoisting apparatus thus adjusted to different duty, without disturbing the relation of the parts or requiring any changes in their construction or arrangement. It will 45 also be seen that the forms of the drums and sheaves, and their particular arrangement may be changed and that other variations may be made without departing from the scope of the invention.

50 What I claim is:

1. The combination of a winding drum, a cable adapted to be wound thereon and connected with a variable load and means for varying the power applied to the drum to 55 correspond with variations in the load comprising another drum operatively connected with the first drum and having a face inclined toward its axis, a cable adapted to be wound on said tapering face, and a third drum connected with a source of power upon 60 which the last named cable is adapted to be wound, said drum having a winding face

constantly maintained at an angle to the axis of the second drum.

2. In combination with the mechanism of 65 claim 1, a sheave over which the first cable travels, said sheave being mounted to have movement parallel with the axis of the first drum.

3. In the mechanism of claim 1, the winding face of the third drum increasing in diameter toward the axis of the second drum.

4. In the mechanism of claim 1, the said angle of the winding face of the third drum to the axis of the second drum being approximately 75 a right angle.

5. The combination of a winding drum, a cable adapted to be wound thereon and connected with a loading device, a sheave between the drum and the loading device over 80 which said cable runs, said sheave being mounted to have movement bodily parallel with the axis of the drum, another drum rigidly connected with the said winding drum and having a face inclined toward its 85 axis, said two drums being mounted on the same shaft, and a cable winding on the inclined face of the said second drum.

6. In a device of the character described, the combination of a winding drum having 90 an inclined face providing a winding surface of varying diameter a shaft upon which said drum is mounted, a second winding drum and a shaft upon which it is mounted disposed substantially at right angles to the shaft of the first drum, and a cable connected with both drums and adapted to be wound alternately on one and then the other of said drums.

7. In a device of the character described, 100 the combination of a winding drum having an inclined face providing a winding surface of varying diameter a shaft upon which said drum is mounted, a second winding drum and a shaft upon which it is mounted 105 disposed substantially at right angles to the shaft of the first drum, and a cable connected with both drums and adapted to be wound alternately on one and then the other of said drums, said cable being secured to a portion 110 of the second drum which is removed from the plane of the shaft of the first drum and the said face of the first drum being inclined toward its axis, and said cable being secured to said drum at the portion of the inclined winding face nearest to its axis, whereby as the cable winds on one drum and unwinds from the other it is maintained substantially 115 normal to the radii of the drums.

Witness my hand this 20th day of November, 1923, at the borough of Dunellen, in the county of Middlesex, State of New Jersey.

JOSEPH C. LUKACHOVIC.
